FRANK W. ROBINSON, OF READING, PENNSYLVANIA, ASSIGNOR TO SCHUYLKILL HOSIERY MILLS, INC., OF READING, PENNSYLVANIA, A CORPORATION OF PENNSYLVANIA.

STRIPING MECHANISM FOR KNITTING MACHINES.

Application filed January 5, 1921. Serial No. 435,215.

To all whom it may concern:

Be it known that I, FRANK W. ROBINSON, a citizen of the United States, residing at Reading, in the county of Berks and State of Pennsylvania, have invented certain new and useful Improvements in Striping Mechanism for Knitting Machines, of which the following is a specification.

My invention relates to the manufacture of circularly knitted stockings, and particularly to the ornamentation thereof by a vertical striping thread introduced with the usual knitting thread to determined needles; and it consists in improved striping-thread carrier mechanism, with means for cooperatively actuating the same and selected needles, and in the improved product producible thereby, as fully set forth in connection with the accompanying drawings and specifically pointed out in the claims.

Fig. 1 is a sectional elevation showing my improved mechanism in preferred form, in connection with known knitting machine elements.

Fig. 2 is a corresponding elevation taken at right angles to Fig. 1.

Fig. 3 is a fragmentary plan view showing one of the jack-lift cams, and indicating a series of jacks for the striping needles.

Fig. 4 is a sectional plan view taken on the line 4—4 of Fig. 1.

Fig. 5 is a sectional view on the line 5—5 of Fig. 1, indicating diagrammatically, in connection with the corresponding view of Fig. 6, the needle-engaging swing of the striping-thread finger.

Fig. 7 indicates a stocking having characteristic single-thread ornamentation effected by my improved mechanism.

The needle cylinder B, as indicated, is of the well known rotary type, carrying a circular series of needles b to which the vertical movements incident to ordinary knitting are imparted by relatively fixed cam mechanism; the latter, as well as other commonly used knitting machine parts being omitted so far as their showing is not required for the proper setting forth of my invention. This needle cylinder is shown as of sufficient length to permit of providing in connection with determined needles guided therein, a series of jacks 10 which are separately slidable in the respective needle

grooves to independently raise such needles; and pattern controlled mechanism for effecting such raisings is illustrated to effect the positioning of the needles required for desired cooperation therewith of my improved striping thread mechanism.

This striping thread mechanism, as shown, is carried by a bracket 11, rigidly fixed to the machine frame 12. The overhanging horizontal arm 13 of this bracket has an apertured end 14, to which is fixed a vertically depending carrier bar 15 in line with the machine axis and having a cam-sleeve 16 thereon extending below the shoulder.

This sleeve 16 is held non-rotatively but axially slidable on the bar, by a guide pin 70 or pins 17 passing through a fixed collar 18 on the bar as indicated; and is connected by a link 19 to a pattern-operated lever 20 pivoted at 21 to the bracket arm, so that the cam devices 22, 23, and 24 of the sleeve may be moved into or out of the path of the splicing-thread carrier device 25—26 as hereinafter fully described.

Two of these thread carrier devices, as shown, are oppositely secured to a rotary sleeve 30 which is rotatably mounted on an axial extension 15^b of the fixed carrier bar 15 and is provided with a forked arm 31 arranged in loose engagement with an inward projection 32 of the needle cylinder so as to be rotated with the latter; the devices being thus swung around the relatively fixed cam sleeve 16.

Each carrier device comprises a main part 25 which is pivoted at 25^a to a fixed collar 90 on the sleeve 30 so as to swing in a radial plane; and a thread finger part 26 having an angularly arranged shank portion 26^a rotatively mounted in said part 25. The head portion 25^b of the latter is pressed against the cam sleeve 16 by a spring 41, as indicated, which retains the threaded end of the finger 26 inside of the circle of needles, as indicated, to the left of Figure 1, excepting when the cam depression 22 of the sleeve 16 permits radial movement of said head portion 25^b to move the finger 26 outside of the circle of needles, as indicated, to the right of said Figure 1. In connection with this radial movement of the finger 26 with the part 25, a turning movement relative to the

latter and approximately in line with the circular series of needles, is imparted to the threaded end of the fingers by means of an arm 26^b on the shank portion 26^a; said arm 5 being arranged to strike the depending contact rod or cam device 23 of the sleeve 16 when the latter is in lowered operative position, so as to turn the finger shank in its mounting in part 25, against the torsional 10 action of a spring 44 which returns it to a normal position as determined by a suitable fixed stop.

The joint effect of the described radial-plane swing of the thread carrier part 25 and circular swing of the finger 26, is to cause the latter to carry its thread to the outside of the circular series of needles, and a determined distance along the needle line so as to cause the thread to engage with any 20 needles within such distance which are so raised as to cooperate in the engaging action, and finally to return to starting position; this engaging movement being indicated in Figs. 5 and 6 as supplying the 25 striping thread to two separated raised groups of three needles each which are included within the determined circular swing of the finger 26.

To insure that the thread thus supplied to 30 these selected needles, will be uniformly placed exterior to the usual knitting thread thereon, I provide for effecting an additional vertical movement of the finger 26 relative to the main part 25 of the thread carrier device, 35 by securing to the sleeve 16 the so-called plating-cam 24, so arranged as to contact with the upper end of the finger shank 26^a and to properly depress the finger and the needle engaging striping thread; against the 40 upward pressure of spring 44 which also exerts the torsional strain upon said shank previously referred to. As illustrated in Fig. 1 the outward swing of the thread finger upon the pivotal connection 25^a, 45 raises the threaded end of the finger, while the plating cam 24 enables any desired lowering of it to insure the proper placing of the thread.

It will be understood that the determined 50 needle-engaging movements of the striping-thread carrier devices 25-26 will be regularly effected at each machine revolution whenever the cam sleeve 16 is lowered to the striping position indicated in Fig. 55 1. In order that these movements may be effective upon any determined needle or needles within this fixed needle-engaging swing, I provide a pattern-controlled mechanism for independently raising any of such 60 needles as desired, to thread-engaging position; in connection with a depressing cam therefor. Thus two raised groups of three needles each are indicated in Figs. 5 and 6, as being engaged by the striping thread, 65 while the lower intervening needles are not

engaged, the effect of which is to produce in the stocking product illustrated in Fig. 7, two parallel stripes *w*, *x*; while the lowering of one of these two groups of needles will stop stripe *x*, as at the narrowed and widened heel pocket indicated in Fig. 7, leaving the stripe *w* to continue down the foot portion of the stocking; or if both these groups be lowered and certain intervening needles be raised to engage the 75 thread, a single midway stripe *y* will be produced; while the ornamental arrowhead end *Z* of the stripe may be formed as shown by properly varying the number of jacks which are raised in successive courses. To produce 80 the wide cross-bar V shown in Fig. 7 the whole series of jacks which are shown as included within the swing of the finger 26 must be raised together.

The mechanism shown for thus varying 85 the needles which are raised for engagement of the striping thread by the regularly swung thread fingers 26, comprises a series of jacks 10, which are arranged in the cylinder grooves of fifteen consecutive needles 90 for each finger, as shown; so as to practically form bottom extensions of said needles; and a series of three inclined jack-lift cams, 51, 52, and 53, arranged to be moved into and out of the path of butts 95 formed on the jacks at different heights indicated in Fig. 1, as automatically determined by the pattern wheel. One of these cams is shown in Fig. 3, relative to a whole series of jacks 10 the butts of which are 100 indicated as of three different lengths; so that a limited inward movement thereof will engage only the longest jack-butts located in that path, while further inward movement will also engage shorter butts in the 105 same path; and the other two cams are similarly movable into the path of different length butts on other jacks, arranged in the different planes. These different inward movements of the several cams are automatically effected through jack-levers 55, 110 56, 57 pivot to the machine frame at 68, and having their lower ends riding on pattern wheel sections 69 provided with cam projections 58, 59, 60 of different heights 115 adapted to impart the desired inward swings to the upper ends of said levers; which latter bear against and are spring-connected to the respective jack-lift cams. Rotary movement is imparted to said pattern wheel 120 sections through a pawl 65 operated through bell-crank 66, 67 and connections in well-known manner.

The special depressing cam 50 is provided for the purpose of lowering the needles preliminary to raising selected ones for any desired striping by determined operation of their jacks. It normally swings upward freely upon its pivot 70, but is held in inclined lowering position at determined 125 130

times by a lever 71 which is operated through a bell-crank 72 by a pattern-wheel connection 73.

It will be understood that the described pattern-controlled movement of any or all of a determined series of needles into and out of the fixed needle-engaging swing of the thread-carrier fingers, satisfactorily effects such clock-work ornamentation of the 10 knitted fabric as is indicated, and that the mechanism and operation specifically set forth may be readily modified.

What I claim is:

1. In combination with a knitting machine 15 having needle-cylinder and operating-cam mechanisms; a striping-thread carrier device comprising a pivoted part arranged to swing in a radial plane and a thread-carrying finger rotatively mounted in said 20 radially-swingable part; and cam devices operative respectively upon said swinging and rotative parts to jointly produce needle-engaging movements of said finger.
2. In combination with a knitting machine 25 having needle-cylinder and operating-cam mechanisms; a radially and rotatively movable striping-thread finger; cam devices operative thereon to produce regular needle-engaging movements of said finger; and a 30 pattern-controlled series of jacks independently operative upon determined needles to temporarily raise them into cooperative relation to said finger.
3. In combination with a knitting machine 35 having needle-cylinder and operating-cam

mechanisms; a radially and rotatively movable striping-thread finger; cam devices operative thereon to produce regular needle-engaging movements of said finger; a pattern-controlled series of jacks independently 40 operative upon determined needles to temporarily raise them into cooperative relation to said finger; and a pattern-controlled needle-depressing cam.

4. In combination with a knitting machine 45 having needle cylinder and operating-cam mechanism; a striping-thread carrier device comprising a pivoted part arranged to swing in a radial plane, and a thread-carrying finger having an angularly-arranged shank portion slidably and rotatively mounted in said pivoted part; a cam device operative upon said pivoted part; and separate cam devices operative upon said shank portion of the finger to respectively turn 55 and slide the same.

5. In combination with a knitting machine having needle-cylinder and operating-cam mechanisms; a radially and rotatively movable striping-thread finger; cam devices 60 operative thereon to produce regular needle-engaging movements of said finger; a series of jacks operative upon determined needles and provided with butts of different lengths arranged at different heights, and a plurality of pattern-operated jack-lift cams arranged in the respective jack-butt paths.

In testimony whereof I affix my signature.

FRANK W. ROBINSON.
